UNITED STATES PATENT OFFICE.

FREDERICK STICKEL, OF CHICAGO, ILLINOIS.

AIR GAUGE.

Application filed December 26, 1924. Serial No. 758,226.

This invention relates to new and useful improvements in air gauges and more particularly to an air gauge which is used for registering air pressure under various conditions. The main object of my invention is the provision of an air gauge operated by air under pressure whereby the pressure of the air may be quickly and readily ascertained.

Another object of my invention is the provision of an air gauge which may be used in an air pump line for designating the pressure of air being pumped and also may be used equally as well for testing the air pressure in pneumatic tires.

A further object of my invention is the provision of an air gauge wherein the pressure of the air operates spring pressed members and novel means is provided for taking up the tension of these springs in accordance with the wear thereon.

With the above and other objects in view, the invention consists in the novel features of construction, the combination and arrangement of parts hereinafter more fully set forth, pointed out in the claims and shown in the accompanying drawings, in which:

Fig. 1 is a vertical section taken through my improved air gauge parts of the same being illustrated in elevation,

Fig. 2 is a sectional view through the casing illustrating parts of the device in elevation,

Fig. 3 is a detail, vertical, sectional view partly in elevation illustrating another form of my invention, and

Fig. 4 is a section illustrating a modified detail.

In carrying out my invention, I provide a cylindrical casing 1 and formed integral with this casing are sleeves 2 and 3 arranged on opposite sides of the casing as shown in Figure 1. The sleeve 3 projects considerably beyond the outer wall of the casing 1 and has a restricted opening 4 through which is inserted a flexible tube 5, the inner closed end of which abuts against a plunger 6 which is mounted for reciprocating movement within the sleeve 3.

Threaded upon the lower end portion 6' of the sleeve 3 is a retaining nut 7' serving in its principal capacity to clamp the flange 22 between itself and the flange 8. This retaining nut has a central passage 8' formed

therein in alignment with the interior 9' of the tube 5 for receiving the outer end portion of a valve stem (not shown) for depressing the valve stem to permit escape of air from the pneumatic tube into the interior of the tube 5.

Arranged within the sleeve 3 and enclosing the tube 5 is an expansion spring 7, the inner end of which is attached to the plunger 6 while the outer end thereof bears against the annular flange 8 formed in the outer end of the sleeve 3.

Connected to the plunger 6 is a rack bar 9, the upper end of which extends up through the sleeve 2 and has a plunger 10 thereon which is mounted for reciprocating movement within the sleeve 2. The inward movement of the plunger 10 is limited to the end of the sleeve by means of an in-turned flange 11 against which the plunger 10 abuts as shown in Figure 1.

The outer end of the sleeve 2 is internally threaded as shown at 12 and engaged therewith is the threaded reduced portion 13 of the adjustable cap 14. The bore 15 within the cap 14 is adapted to receive the upper end of the rack bar 9 which projects through an opening 16 at the outer end of the cap 14 so that the upper end of the rack bar may be slidably mounted within the sleeve 2 and cap 14.

Arranged within the sleeve 2 and cap 14 is a compression spring 17 which normally bears against the plunger 10 in order to retain the same against the annular flange 11. As shown in Figure 1, the spring 7 serves to support the tube 5 in a vertical position with its closed end portion 10' in abutting relation with the plunger 6 when the plunger 6 is in its lowermost position within the sleeve 3.

Extending transversely through the casing is a shaft 18 upon which is mounted a pinion 19, the outer end of the shaft carrying an indicator 20 which moves over the graduated face 21. The pinion 19 is adapted to mesh with the rack bar 9 whereby upon movement of the rack bar within the casing 1, the indicator 20 will be moved over the graduated face 21. Attention is directed to Figure 1 wherein it will be noted that the tube 5 is retained in position by having an annular flange 22 formed around its outer end and secured in any suitable manner to the annular flange 8 on the sleeve 3, thus

when the tube 5 is expanded it will prevent the outer end thereof from being drawn into the sleeve.

In operating my improved device, the air pressure line is connected to the outer end of the sleeve 3, the air pressure passing into the tube 5 and expanding the same longitudinally of the sleeve 3. This movement expanding the spring 7 and contracting the spring 17, also reciprocating the plunger 6 in the sleeve 3 and the plunger 10 in the sleeve 2, which movement will cause the rack bar 9 to rotate the shaft 18 through its engagement with the pinion 19 for moving the indicator 20 over the graduated dial 21. From this it will be apparent that as soon as the air pressure is released, and the tension removed from the two springs 7 and 17, the plungers will return to their normal positions moving the indicator back to the zero mark on the dial.

In Figure 3, I have illustrated a slightly modified form of my invention wherein the casing 1 has a sleeve 23 extending from one side thereof and provided with an angular retaining sleeve 24 at its outer end. The sleeve 24 in the present instance is held in operative relation with the sleeve 23 by reason of frictional engagement between these sleeves. This sleeve 24 has an inwardly extending flange which supports the enlarged end head portion 25 of the tube 26, the inner end of the tube abutting against the plunger 27. This plunger 27 is connected as an integral part of a rack bar 28 by means of the rod 29, said rack bar having engagement with a pinion 30 which is mounted upon a shaft 31 for actuating the indicator 32. The indicator 32 moving over the graduated dial 21, the same as in the preferred form of the invention.

Arranged between the head member 25 and the plunger 27 is an expansion spring 33, one end of which is connected to the plunger 27. Mounted upon the rod 29 and disposed between the plunger 27 and an adjustable plug 34 is a compression spring 35. The plug 34 is adjustable within the inner end of the sleeve 23 in order to take up the tension lost in the springs 33 and 35 due to the constant use thereof. It will be noted that in the form of the invention shown in Figure 3, the operation is the same as in the preferred form of the invention, the only difference being that the two springs are arranged in close proximity, one to another, and enclosed within a single sleeve. The adjustable plug may be readily turned by passing an instrument (not shown) through the opening 36 formed in the retaining plate 37 and inserting the end portion of the instrument in a transverse slot 34' formed in the plug 34 for increasing the tension or decrease the tension of the springs 33 and 35.

The sleeve 24 includes an inwardly annu-

lar flange 24' defining a central passage 25' in alignment with the interior of the tube 26 for receiving the outer end of a valve stem (not shown) to depress this valve stem to permit the escape of air from the pneumatic tube (not shown) with which the valve stem is associated, and pass into the interior of the tube 26.

In Figure 4, I have illustrated another form of the invention wherein the springs 75 are eliminated and a comparatively heavy tube 38 is arranged within the outer end of the sleeve either the sleeve 3 or 23 being used in this form. The inner closed end of the tube 38 bears against the plunger 39 so that when air pressure is passed into the tube the same will expand and operate the indicator in the same manner as in the other forms of the invention.

It will be apparent from the foregoing 85 that by the use of my improved air gauge, the air pressure in air pump lines, pneumatic tires or the like may be readily ascertained and the tension of the springs used in connection with the gauge may be readily 90 adjusted.

While I have shown and described the preferred embodiment of my invention, it will be understood that various changes and alterations may be made without departing 95 from the spirit of the invention or the scope of the appended claims.

Having thus described my invention, what I claim is:

1. An air gauge including a casing, a graduated dial carried by the casing, an indicating finger movable over the dial, an operating member for the indicating finger and movable transversely of the casing, opposite aligned sleeves formed as an integral part of the casing, a plunger carried by the operating member at one end thereof and adapted to work in one of the sleeves, an expansible tube confined in said one of the sleeves, and having a closed end portion in abutment with the plunger, said expansible tube being adapted to be expanded by an air pressure for moving the operating member in a certain direction transversely of the casing, a resilient member embracing the expansible tube for supporting said tube in substantially a straight line, the open end of said tube being disposed exteriorly of said one of the sleeves, a plunger carried by the operating member at the other end thereof and adapted to work in the other of the sleeves, and a spring member confined in said other of the sleeves and operable upon said last mentioned plunger for moving operating member in an opposite direction.

2. An air gauge including a casing, a graduated dial carried by the casing, an indicating finger movable over the dial, an operating member for the indicating finger and movable transversely of the casing, a plunger

carried by the operating member at one end thereof and adapted to work in one of the sleeves, an expansible tube confined in said one of the sleeves, and having a closed end portion in abutment with the plunger said expansible tube being adapted to be expanded by an air pressure for moving the operating member in a certain direction transversely of the casing, a resilient member embracing the expansible tube for supporting said tube in substantially a straight line, the open end of said tube being disposed exteriorly of said one of the sleeves, a plunger carried by the operating member at the other end thereof and adapted to work in the other of the sleeves, a spring member confined in said other of the sleeves and operable upon said last mentioned plunger for moving said operating member in an opposite direction, and an adjustable member threaded into said other of the sleeves and operable upon the spring member for adjusting the tension of said spring member.

3. An air gauge including a casing, a graduated dial carried by the casing, an indicating finger movable over the dial, an operating member for the indicating finger and movable transversely of the casing, opposite aligned sleeves formed as an integral part

of the casing, a plunger carried by the operating member at one end thereof and adapted to work in one of the sleeves, an expansible tube confined in said one of the sleeves, and having a closed end portion in abutment with the plunger, said expansible tube being adapted to be expanded by an air pressure for moving the operating member in a certain direction transversely of the casing, a resilient member embracing the expansible tube for supporting said tube in substantially a straight line, the open end of said tube being disposed exteriorly of said one of the sleeves, a plunger carried by the operating member at the other end thereof and adapted to work in the other of the sleeves, a spring member confined in said other of the sleeves and operable upon said last mentioned plunger for moving said operating member in an opposite direction, an adjustable member threaded into said other of the sleeves and operable upon the spring member for adjusting the tension of said spring member, and an annular inturned flange formed on said other of the sleeves adapted to limit movement of the plunger in said opposite direction.

In testimony whereof I affix my signature.
FREDERICK STICKEL.
